UNITED STATES PATENT OFFICE.

BROADUS S. ALLEN, OF GAFFNEY, SOUTH CAROLINA, ASSIGNOR, BY MESNE ASSIGNMENTS, TO MAY B. LIPSCOME.

FOLDING CRATE.

Application filed June 24, 1920. Serial No. 391,300.

To all whom it may concern:

Be it known that I, BROADUS S. ALLEN, a citizen of the United States, residing at Gaffney, in the county of Cherokee and State of South Carolina, have invented certain new and useful Improvements in a Folding Crate, of which the following is a specification.

This invention relates to shipping crates 10 of the folding or collapsible type.

The object of the invention is to provide a simply constructed, cheap and efficient crate of this character which will occupy a minimum amount of space when collapsed 15 and which may be quickly set up and collapsed when desired.

With this and other objects in view, the invention consists in certain novel features of construction as hereinafter shown and described and then specifically pointed out 20 in the claim hereunto appended.

In the accompanying drawings:

Figure 1 represents a perspective view of the crate constituting this invention shown 25 in setup operative position.

Fig. 2 is an end elevation of the crate in setup position.

Fig. 3 is a similar view of the crate in collapsed position, and,

Fig. 4 is a longitudinal section of the 30 crate in collapsed position.

In the embodiment illustrated the crate constituting this invention comprises a base or bottom member 1 preferably rectangular in configuration and having fixed side members 2 and 3 secured to the outer side edges thereof the side member 2 being about twice as wide, more or less, as the member 3 for a purpose presently to be described. Hinged 35 to these fixed side members 2 and 3 are foldable side members 4 and 5, the member 5 which is wider than the member 4 being hinged to the narrow fixed member 3 and the member 4 hinged to the wider fixed member 2 so that when the crate is set up 40 the sides thereof will be of equal height.

End members 6 and 7 are hinged at their lower edges to the outer end edges of the base 1 and are designed to fold inwardly on said member when the crate is collapsed. The hinges employed for connecting these end members to the base are so constructed 45 as to permit the end members to fold inwardly and to hold them in vertical position when opened up and prevent them

from opening outwardly beyond such position. These end members correspond in width to the distance between the fixed side members 2 and 3 being of the same width as the base member 1 and the height thereof 60 is slightly greater than that of the combined hinged and fixed side members the difference in height being equal to the thickness of the top members 8 and 9 which are hinged to the upper edges of the side members 4 and 5 and are adapted to fold between the upper edges of the end members 6 and 7 when the crate is in closed operative position. (See Fig. 1.)

The end members 6 and 7 are provided in 70 their upper edges with cutout portions or recesses 10 which are here shown formed midway the width of said end members and are designed to receive longitudinally extending tongues 11 carried by the free edges 75 of the top members 8 and 9 the two tongues 11 being of a width to correspond to the length of the recess 10 and fitting snugly therein as is shown clearly in Figs. 1 and 2 so that when the crate is in setup position 80 these tongues will be interlockingly engaged with the end members and hold the parts in operative position.

Sliding latches or pins 12 are preferably carried by the ends 6 and 7 and are adapted 85 to project into the recesses 10 thereof. One of these pins is mounted adjacent each end of each recess and are designed to enter sockets or bores 14 formed in the tongues 11 opposite the grooves or seats in the ends in which 90 said pins are mounted. These pins are preferably provided with curved heads 15 which are adapted to be turned down into seats 16 so as to prevent the pins from slipping out after having been placed in position for 95 locking the tops 8 and 9 in operative position.

The hinged side member 5 is preferably provided with an eye 17 to receive a hook 18 carried by the other side member 4 when the 100 crate is in collapsed position for locking the parts in this position.

In the use of this crate the parts being in setup operative position as shown in Fig. 1 when it is desired to collapse it for shipment 105 or other purposes the top members 8 and 9 are raised sufficiently to release the tongues 11 from the recesses 10 and the end members 6 and 7 are then folded downwardly and inwardly flat against the base member 1. The 110

tops 8 and 9 are then folded inwardly flat against the inner faces of the side members 4 and 5 and the side member 5 carrying the top 9 is folded down over the end members 6 and 7 as is shown clearly in Fig. 3. The other side member 4 carrying the folded top 8 is then folded inwardly until said top 8 rests on the outer face of the side member 5. When the parts are in this position the 10 crate will be collapsed and will be held in this position by the engagement of the hook 18 with the eye 17 above described.

It will thus be obvious that making the 15 fixed side members 2 and 3 of different heights the folding of the top and side members may be compactly effected as is shown clearly in Fig. 3.

The preferred embodiment of the invention is disclosed in the drawings and set 20 forth in the specification, but it will be understood that any modifications within the scope of the claim may be made in the con-

struction without departing from the principle of the invention or sacrificing any of its advantages.

What I claim is:

A crate comprising a foldable body having recessed end walls, said recesses opening through the top edges of said walls, a sectional top carried by the body, supporting 30 tongues on the opposite ends of each section of the top and adapted to be seated in said recesses when the top is closed and the body set up, and oppositely disposed manually operable fasteners concealed within each of the end walls and slideable through the side walls of the recesses to engage and lock in the adjacent tongues at one end of the top sections when seated in the recesses, thereby fastening the said sections of the top closed. 40

In testimony whereof, I affix my signature hereto.

BROADUS S. ALLEN.
